UNITED STATES PATENT OFFICE

168,892

LABORATORY SPECIMEN PRESS

George W. Graves, Oak Park, Ill., assignor to
Buehler, Ltd., Chicago, Ill., a copartnership

Application October 26, 1951, Serial No. 17,126

Term of patent 7 years

(Cl. D63—1)

To all whom it may concern:

Be it known that I, George W. Graves, a citizen of the United States and a resident of Oak Park, in the county of Cook and State of Illinois, have invented a new, original, and ornamental Design for a Laboratory Specimen Press, of which the following is a specification, reference being had to the accompanying drawing, forming part thereof.

Figure 1 is a perspective view showing the front, top and one side of a laboratory specimen press showing my new design; and

Figure 2 is a perspective view showing the front, top and the other side thereof.

The back of the press, not shown, is substantially plain.

I claim:

The ornamental design for a laboratory specimen press, as shown and described.

GEORGE W. GRAVES.
